SKIMMING DEVICE

John J. Pluta, Nickolas L. Mayer, and Harry M.
St. John, Chicago, Ill., assignors to Crane Co.,
Chicago, Ill., a corporation of Illinois

Application November 23, 1944, Serial No. 564,846

1 Claim. (Cl. 22—83)

1

This application refers to a portable skimming device and more particularly to a device for skimming the surface of molten metal in a crucible or ladle during the pouring of a metal into a mold so that dross and foreign matter cannot enter the mold with the metal.

We are aware that portable skimmers have been used in the past for the above purpose, but to our knowledge no one has previously devised one capable of performing in the improved manner hereinafter set forth.

More particularly, our invention relates to a novel construction of a skimming device in which the material used for the article may be preferably of a non-wetting nature, as for example of the order of artificial graphite.

Another important object is to provide for a skimming block having a novel form of tapered hole or passage of varied depth to insure effective skimming throughout the pour.

Another object is to provide an improved skimmer with a rounded opening at the spout imparting to the stream a desired shape for pouring and with a relatively flattened opening at the inner end of the skimmer block to produce thorough skimming of the metal even when the ladle is nearly empty.

Another object is to provide a skimmer in combination with a novel pivoting rod arrangement making it convenient to swing the skimming block out of the way when the ladle is being filled and bringing it accurately back into desired position within the ladle before the pouring operation.

The advantage of using a material which does not wet but which effectively skins the molten metal permits the block and its passage to stay clean from dross and oxides which would otherwise clog the channel and hinder the flow of metal.

Another advantage of the structure lies in providing a skimmer with a relatively long and tapered pouring slot of varying depth which results in effective skimming even when the ladle is nearly empty and the surface of the metal is almost in line with the central axis of the pouring surface of the ladle. Thus the skimming operation is more thorough than when it is done manually or by the means previously available.

Another important object is to provide a skimmer with a passage throughout lending itself not only to effective skimming but also permitting accurate pouring into the sprue opening of the mold.

Other objects and advantages will become readily apparent in connection with the following de-

2

scription read in light of the accompanying drawings, in which

Fig. 1 is a fragmentary sectional view of a skimming device embodying our invention when assembled with a conventional pouring ladle.

Fig. 2 is a plan fragmentary view of the assembly described in connection with Fig. 1.

Fig. 3 is a front view of our novel skimming device.

10 Fig. 4 is an enlarged perspective view showing the novel pouring passage of our invention.

Referring to Fig. 2, the skimming block generally designated 1 is attached as at 2 to the pivot rod 3, the latter member being arcuately movable from a position within the upper rim portion of the ladle 4 by being pivotally mounted at 5 to move within the ladle opening 6 to make an inner peripheral contact therewith, as indicated. The purpose of the pivotal arrangement referred

15 to is to permit the skimming block to be moved out of the way when the ladle is being filled and also to permit returning it accurately into position preliminary to the metal pouring operation.

It has been found preferable to make the head

20 portion 7 of the skimming block of a thickness at least equal to one-fifth of the ladle depth for improved skimming action. The head 7 has a reduced transverse extension 8 for purpose of attachment to the pivot rod 3 as hereinabove referred to.

25 It should be understood that while it is important, it is not absolutely essential that the material of the skimming head 7 should be non-wetting with respect to the molten metal. Its detailed structural shape, as above described, 30 may likewise be varied.

A significant element of our contribution lies also in the novel form of a tapered pouring passage which insures effective skimming throughout the pour. That is to say, our skimmer is

35 equally efficient in its performance when the ladle approaches nearly a horizontal position as it is being emptied. This desirable pouring objective is attained as more clearly shown in Fig. 4. In the latter figure the substantially semi-

40 circular opening 9 on the block 1 at the spout or pouring end of the ladle forms a pouring stream of molten metal of desirable shape permitting accuracy when filling the mold, while at the opposite end thereof and gradually approaching such

45 opening at the inner end now referred to, the flattened opening 11 provides for more thorough skimming when the ladle is nearly empty because of the reduced height of the latter aperture and its broader span. The cross-sectional area of the 50 passage thus defined is preferably unchanged

55

from that of the opening 9 so that it is practically constant throughout its length, and further insures effective skimming and a uniform metal stream whether the ladle is full or is nearly empty. Thus after the skimmer block 1 is placed in operative position, and the ladle 4 is gradually tilted to pour the metal therefrom, the inner edge of the skimmer block engages the slag and like impurities holding them back so that they will not pass from the ladle. After the metal has been poured, the impurities may be dumped or otherwise disposed of.

It is apparent that a relatively simple type of skimming device has been provided and its detailed form may vary substantially from that embodiment shown without extending beyond the scope of the claim appended hereto.

We claim:

A skimmer suitable for removable attachment to a ladle of the character described, the said skimmer having a body portion for pivotal mounting upon the ladle and a head portion thickened relative to the body portion, the said head portion having a curved surface which contacts throughout with the ladle at an annular inner surface portion of the ladle adjacent to the rim of the latter, the portion of the curved surface of

the thickened head in contact with the ladle being interrupted by a grooved passage extending through a substantially medial portion thereof for the flow of molten metal therethrough, the said passage on its longitudinal axis being tapered in a plurality of planes and the depth of the said passage being greater at that portion of the head immediately adjacent the ladle rim than at the opposite or lower end of the passage on the head portion, the cross-sectional area of the passage being substantially constant throughout its length.
